UNITED STATES PATENT OFFICE.

GEORGE W. WHITEMAN, OF PHILADELPHIA, PENNSYLVANIA.

ANTICREEPING DEVICE FOR RAILS.

No. 914,095.

Specification of Letters Patent.

Patented March 2, 1909.

Application filed July 21, 1908. Serial No. 444,583.

To all whom it may concern:

Be it known that I, GEORGE W. WHITEMAN, a citizen of the United States, residing in the city and county of Philadelphia, State of Pennsylvania, have invented a new and useful Anticreeping Device for Rails, of which the following is a specification.

The tendency of railway rails to creep longitudinally especially on grades is the cause of constant trouble and expense since at comparatively frequent intervals it is necessary to shorten certain of the rails in order to make up for such longitudinal movement thereof.

One of the main objects of my present invention is to design a novel construction of a device which will prevent such improper longitudinal movement of the rails after they are laid in the track, and also to devise a construction which may be cheaply manufactured, and also be durable and efficient in practice.

To the above ends, my present invention consists of a novel construction of an anti-creeping device for railway rails whereby any longitudinal creeping movement of the rail is prevented.

It further consists of a novel construction of a tie plate and novel means carried thereon by adapted to co-act with the base flange of the rail in such a manner that any creeping or longitudinal movement of the rail will cause such fastening device to bite into and more firmly engage the flange so that such longitudinal creeping of the rail will be positively prevented.

It further consists of a novel construction of a locking member which prevents any lifting of the rail and which is mounted in such a manner that any longitudinal movement of the rail causes such member to more firmly engage with the base flanges of the rail.

It further consists of other novel features of construction all as will be hereinafter more fully set forth.

For the purpose of illustrating my invention I have shown in the accompanying drawings those embodiments thereof which will give in practice satisfactory and reliable results, although it is to be understood that the various instrumentalities of which my invention consists can be variously arranged and organized and that my invention is not limited to the precise arrangement and

organization of these instrumentalities as herein set forth.

Figure 1 represents a perspective view showing an anti-creeping device embodying my invention in operative relation with respect to a rail and the rail tie. Fig. 2 represents a plan view of the anti-creeping device seen in Fig. 1. Fig. 3 represents a sectional elevation on line $x-x$, Fig. 2, of the anti-creeping device and showing also a portion of a rail in operative relation therewith. Fig. 4 represents a plan view of another embodiment of my invention in which two cam members are located on opposite sides of the rail for preventing any improper longitudinal movement thereof. Fig. 5 represents a plan view of another embodiment of my invention in which a plurality of cam members are employed to prevent the improper longitudinal movement of the rails. Fig. 6 represents a sectional elevation on line $y-y$, Fig. 5, but showing in addition a portion of a rail in operative relation with respect to the anti-creeping device. Fig. 7 represents a sectional plan view of another embodiment of my invention. Fig. 8 represents a section on line $z-z$ Fig. 7 but showing in addition a portion of a rail in operative relation with respect to the anti-creeping device.

Similar numerals of reference indicate corresponding parts in the figures.

Referring to the drawings:—1 designates a portion of a railway tie to which my novel construction of tie plate 2 is adapted to be securely fastened, it being noted that the tie plate 2 is provided with depending lugs or projections 3 which are preferably angularly inclined with respect to each other and which are adapted to engage and extend into the rail tie 1 when the device is secured thereto.

4 designates a flange or abutment preferably integral with the tie plate 2 and having its under surface 5 preferably of such contour that the base flange of the rail 6 may engage therewith. The rail 6 may be of any usual or conventional type and in the present instance I have preferred to show the same as being of the usual T form of construction provided with base flanges which are adapted to rest upon the tie plate 2 and to be secured thereto by means of the usual type of fastening spikes 7 which pass through the tie plate 2 into the railway tie 1.

8 designates a bearing lug or bracket located on the side opposite the flange 4 and preferably made integral with the tie plate 2. The inner surface of the bearing lug 8 is provided with a circular recess as seen at 9, it being understood from Fig. 3 that the inner face of this recess 9 is preferably concave as indicated at 10 in Fig. 3.

11 designates a locking member having a bearing surface 12 which engages the concave bearing surface 10 of the lug 8.

13 designates a fastening device such as a rivet, bolt or equivalent device which passes through the locking member 11 and the tie plate 2, as will be clearly understood from Figs. 2 and 3, so that the locking member is eccentrically mounted and forms a locking cam member. The member 11 is preferably provided on its operative cam surface with the teeth or indentations 14 which are adapted to bite into and indent the side of the flange of the rail, as will be readily understood by reference to Figs. 1 and 3.

In order to positively prevent any loosening of the locking member 11 after it has been fixed in position, it is advantageous in some cases to provide the same with a shoulder 15 between which and the lug 8 is interposed a spring 16 in order to prevent improper rearward movement of such member 11 after the same has been placed in assembled position with respect to the rail, although it is to be understood that in many cases arising in practice such spring 16 may be dispensed with. The tie plate is provided with suitable apertures 17 through which the spikes 7 pass in order to fasten the tie plate to the railway tie.

In the embodiment seen in Fig. 4 I have shown a construction wherein I have dispensed with the flange or abutment 4 and employ in lieu thereof a locking cam member 18 which is constructed in a manner similar to the cam 11, and I also employ a bearing lug 19 which is constructed in a manner similar to the lug 8. A suitable fastening device is also employed whereby when the rail is placed in position on the tie plate 2 the locking members 11 and 18 will firmly engage with the base flanges of the rail on opposite sides thereof.

In the embodiment seen in Fig. 5 instead of employing a single cam member adapted to engage the flange of the rail on one side of the latter, I employ a plurality of such members and in this embodiment, I have shown the same as consisting of a plurality of arms 21 the operative portion of which is preferably serrated or provided with an irregular surface in order that a better grip on the base flange of the rail may be obtained, it being seen that the members 21 are pivotally secured with respect to the tie plate 2 by means of suitable fastening devices 23, the end of said members 21 oppo-

site to the portions 22 being adapted to engage with the bearing lugs 24 and in this embodiment, as seen in Fig. 6, the inner bearing surface of the lug 24 is preferably concave as indicated at 25 as is also that portion of the 70 cam members 21 which is adapted to engage with the base flange of the rail as is indicated at 26.

In the embodiments which I have thus far described the tie plate is placed in position 75 on the tie, as seen in Fig. 1, between the flange 4 and the locking member or members or between the two locking members and the tie plate and the rail is then spiked to the tie.

In the embodiment seen in Figs. 7 and 8, I have shown a slightly modified construction in which the tie plate 2 is provided with a flange or abutment 4 in a similar manner to that seen in Figs. 1, 2, 3, 5 and 6, but in this embodiment I employ a movable locking 85 member 27 which is provided with an extension 28, the latter being preferably provided with an irregular surface or serrations 29 adapted to engage with the base flange of the rail as will be clearly understood by reference 90 to Fig. 8. The operative surface of the projection 28 is preferably concave as indicated at 30 in Fig. 8. The member 27 is provided with a beveled or inclined side 31 which engages with the inclined face 32 of the flange 95 33 which latter is preferably integral with the tie plate 2. It will be understood that in this embodiment after the rail has been placed on the tie plate 2 the member 27 is forced forwardly, and since the flange 33 extends at an 100 angle to the longitudinal axis of the tie plate 2, the irregular surface of the extension 28 will bite into and indent the base flange of the rail, thereby causing the same to be more firmly wedged between the locking member 105 27 and the flange or abutment 4, thereby preventing improper longitudinal movement thereof.

It is to be understood that in all the embodiments of my invention the locking members 110 are preferably provided with a concave bearing surface adapted to engage the side of the base flange of the rail whereby any improper lifting or raising of the rail during the operation of traffic is positively prevented. 115

I wish to particularly point out that in my present invention the tie plate is secured to and supported directly upon the railway tie and the rail is supported directly upon the tie plate and the fastening devices which secure the rail to the ties pass through the tie plate and also the ties, so that if the rail starts to creep the rail-way tie itself must be moved but this is prevented by the ballast placed between the rail ties. It will further 120 be apparent that in all the embodiments of my invention the further movement of the locking members after they have once been placed in assembled position, owing to the longitudinal movement of the rail itself, will 125 130

cause these members to more firmly engage with the base flanges and thereby cause the rail to be the more firmly wedged between such locking member or members and the flange of the tie plate where such is employed.

The number of lugs 3 and the number of spike holes 17, as also their location, will vary as will be apparent according to the requirements of conditions met with in practice.

10 The locking cam members may be pivotally mounted on the tie plate 2 by means of any desired type of fastening devices.

In the devices heretofore employed for preventing the creeping of the rails their life has 15 been comparatively short owing to the bolts or rivets for fastening the same in place becoming sheared or broken off due to the great stress thereagainst, and I wish to direct particular attention to my present device for 20 overcoming such defects, since the locking member in each case bears against a bearing lug on the tie plate 2 so that the stress against the fastening device is reduced to a minimum.

In so far as I am aware I am the first in the 25 art to devise a tie plate adapted to be secured on the railway tie and on which the rail is seated, wherein a locking cam member adapted to engage the side of the base flange of the rail is employed, said locking member being 30 rotatably mounted and provided with means for taking up the stress on the fastening devices for such member, and my claims to these features are to be interpreted with corresponding scope.

35 My novel construction of locking members preferably engage only the side of the base flange so that the wedging effect acts directly in alignment with such base flanges.

It will now be apparent to those skilled in 40 this art that I have devised a novel construction of an anti-creeping device which embodies the features of advantage enumerated as desirable in the statement of the invention and the foregoing description, and while I 45 have in the present instance shown and described those embodiments thereof which in practice give satisfactory and reliable results, it is to be understood that the same are susceptible of modification in various particulars without departing from the spirit or scope of the invention or sacrificing any of its advantages.

Having thus described my invention, what I claim as new and desire to secure by Letters 50 Patent is:—

1. In a device of the character described, a tie plate adapted to support the rail and to be secured to the tie and having a rail flange engaging abutment on one side thereof, and a 55 locking cam member movably mounted on the opposite side thereof for engaging the edge of the rail flange.

2. In a device of the character described, a tie plate having a rail flange engaging abut-

ment on one side thereof, and a locking 65 member provided with a concave operative surface movably mounted on the opposite side thereof for engaging the edge of the rail flange.

3. In a device of the character described, 70 a tie plate having a rail flange engaging abutment on one side thereof, and a locking member provided with a serrated concave operative surface movably mounted on the opposite side thereof for engaging the edge of 75 the rail flange.

4. In a device of the character described, 80 a tie plate having a rail flange engaging abutment on one side thereof, a locking cam member provided with an irregular operative cam surface 85 movably mounted on the opposite side thereof for engaging the edge of the rail flange, and a bearing block carried by said tie plate and co-acting with said locking cam member to take up the lateral strain on the 90 latter.

5. In a device of the character described, a tie plate having a rail flange engaging abutment on one side thereof and having depending lugs, and a locking cam member provided 95 with an irregular operative cam surface movably mounted on the opposite side thereof for engaging the edge of the rail flange.

6. In a device of the character described, a tie plate having a rail flange engaging abutment on one side thereof and a bearing block 95 on the opposite side thereof, and a locking member movably carried by said plate and having a portion adapted to engage the rail flange, whereby the rail flange on longitudinal movement thereof will be the more firmly wedged between said abutment and said locking member.

7. In a device of the character described, a tie plate having a rail flange engaging abutment on one side thereof and a bearing block 105 on the opposite side thereof, a locking cam member adapted to engage the rail flange and having a bearing surface engaging said block, and a fastening device for rotatably securing said member to said plate and in engagement with said block.

8. In a device of the character described, a tie plate having a rail flange engaging abutment on one side thereof and a bearing block 115 on the opposite side thereof, and a locking member co-acting with said block and having a concave surface adapted to engage the side of the rail flange whereby the rail flange on longitudinal movement thereof will be more firmly held between said abutment and said locking member.

9. In a device of the character described, a tie plate having a rail flange engaging abutment on one side thereof and a block having 120 a concave bearing surface on the opposite side thereof, and a locking member rotatively carried by said tie plate and having a bearing

surface co-acting with the concave surface of said bearing block, said locking member being adapted to engage with the rail flange.

10. In a device of the character described, 5 a tie plate having a rail flange engaging abutment on one side thereof and a block having a bearing surface on the opposite side thereof, a locking member rotatively carried by said tie plate and having a bearing surface 10 co-acting with the bearing surface of said block, and means for preventing improper rearward movement of said locking cam member.

11. In a device of the character described, 15 a tie plate having a rail flange engaging abutment on one side thereof and a block having a concave bearing surface on the opposite side thereof, and a locking cam member ro-

tatively carried by said tie plate and having a bearing surface co-acting with the concave 20 surface of said bearing block, said locking cam member being adapted to engage with the rail flange.

12. In a device of the character described, 25 a tie-plate adapted to support the rail and to be secured to the tie and having a rail flange engaging abutment on one side thereof, a locking cam member movably mounted on the opposite side thereof for engaging the rail flange, and a bearing block coacting 30 with said cam member to prevent lateral displacement thereof.

GEORGE W. WHITEMAN.
